[57] CLAIM

The ornamental design for a sword hilt, as shown and described.

DESCRIPTION

FIG. 1 is a front elevational view of a sword hilt, showing my new design; the rear being a mirror image thereof;

FIG. 2 is a right side elevational view, the left side being a mirror image thereof;

FIG. 3 is a top plan view thereof; and,

FIG. 4 is a bottom plan view thereof.

The broken line showing of part of a sword blade in FIGS. 1 and 2 is for illustrative purposes only and forms no part of the claimed design.

FIG. 1

FIG. 2

FIG. 3

FIG. 4
